UNITED STATES PATENT OFFICE.

BENJAMIN A. VAUGHN, OF CORNING, CALIFORNIA, ASSIGNOR OF ONE-HALF TO RUDOLPH MADSEN, OF OAKLAND, CALIFORNIA.

CARPENTER'S GAGE.

No. 892,780.

Specification of Letters Patent.

Patented July 7, 1908.

Application filed February 29, 1908. Serial No. 418,517.

To all whom it may concern:

Be it known that I, BENJAMIN A. VAUGHN, a citizen of the United States, residing at Corning, in the county of Tehama and State 5 of California, have invented a Carpenter's Gage, of which the following is a specification.

This invention is an improvement in gages, and relates more especially to that 10 class of such devices which are employed by carpenters, joiners, and other mechanics for the purpose of marking off lines parallel with the edge of a board or other article.

It is a common practice with carpenters 15 and other mechanics in marking off guidelines on boards to use an ordinary two-foot rule by grasping it at a certain point and permitting the index-finger of the hand to follow the edge of the board while the pencil 20 is held at the inner end of the rule so as to mark the line as the rule is moved along the board. This practice frequently results in injury to the finger that is in contact with the edge of the board by reason of splinters 25 or the roughness of the board.

The primary object of my invention is to provide a gage device which may be slidably mounted on the rule and securely held in any adjusted position thereon, the said gage 30 device being of such construction as to form a hand grasping portion and an edge or metal plate which engages the edge of the board and guides the rule in the same manner as the index finger.

35 A further object of the invention is to provide a gage device of this character as a separate article from the rule and therefore removable therefrom so that the rule may be used for its ordinary purposes.

40 The invention consists of a rectangular block having a central longitudinal bore of such size in cross-section as to receive two members of a jointed two-foot rule of standard size, in combination with certain means 45 for clamping the block in an adjusted position on the rule; all as hereinafter fully described and specifically set forth in the appended claims.

In the drawings illustrating my invention: 50 Figure 1 is a plan view showing the application of my improved gage device. Fig. 2 is a side view of the gage device and ruler. Fig. 3 is a longitudinal sectional view through the gage device or attachment. 55 Fig. 4 is a front view.

Like numerals of reference indicate like parts in all the views of the drawings.

In carrying out my invention I employ a metal block 1, which is rectangular in shape and is provided with a central longitudinal 60 bore 2 of such size in cross-section to receive two members of an ordinary two-foot rule, as 3, so that said block may be slidably mounted on said rule, as shown in Fig. 1 of the drawings. Attached to or formed integrally at one end of this block is a metal plate 4, of rectangular shape and of such size with respect to the end of the block as to extend above and below the same, the downwardly-projecting portion of the plate forming that 70 part of the device which engages the edge of the board when the gage is in use, while the upwardly-projecting portion forms a part of the clamping means, hereinafter described. This plate has a transverse opening or slot 5 75 which registers with the bore in the block and is practically a continuation thereof so as to permit the rule to pass through the plate and block.

The upwardly-projecting portion of the 80 front plate 4 is provided with a pair of rearwardly-projecting ears 6 6, spaced apart and pierced transversely to receive a pintle 7, and pivoted between these ears on the pintle is a cam-lever 8. The upper part of the block is 85 cut away below the cam of the lever, as at 9, so that said cam may enter the longitudinal bore of the block and engage the rule. The cam operates at the center of the block so that it may engage both members of the rule, 90 and is so disposed that when the lever is raised the lower surface of said cam will be above the bore so that the block may slide freely on the rule and when said lever is lowered the cam surface will impinge upon the 95 rule to hold the block tightly thereon.

It will be here noted that the construction and disposition of the parts are such that when the lever is lowered to cause the cam to engage the rule the upper portion of the plate 100 4 will slightly yield and thus exert a spring pressure on the clamp that will not only provide a firm engagement with the rule but will also lock the lever in closed position with the handle portion thereof against the upper 105 surface of the block, for which latter purpose the face of the cam is slightly flattened, as at 10.

The operation of the device will be readily understood, for after folding the rule so that 110

it will present two contiguous members, as shown in Fig. 1, the device with the cam-lever raised is slid upon either end of the rule and adjusted thereon a distance from the end 5 according to the desired location of the line from the edge of the board, this adjustment being facilitated by the usual gage-marks on the rule. When the device is properly adjusted the cam-lever is depressed and will 10 securely lock the device on the rule. The rule with the gage device attached is then used after the customary manner of using a rule alone, the hand which guides the rule in the present instance grasping the block so as 15 to force the lower portion of the plate against the edge of the board as the gage is moved along said board, during which operation a pencil, nail, or other pointed instrument, is held against the end of the rule so as to make 20 the necessary mark on the board.

The parts of the device are preferably made of steel, the plate which carries the lugs or ears being made of spring steel to give the required resiliency and so that there 25 will be little if any wear on that face of the plate which travels along the edge of the board. However, the block and the face-plate, including the ears on the latter, may be cast in one piece or formed by drop for- 30 ging, and I therefore do not wish to limit my protection to the particular manner of making up the device, nor to the particular construction of the cam-lever or clamping-device.

35 The gage device provides a very simple and inexpensive attachment for an ordinary rule so that it may be readily converted into a ruling-gage.

Having described my invention, what I 40 claim as new, and desire to secure by Letters-Patent, is:

1. In combination with a rule, of a gage

device comprising a block having a bore ex-
tending longitudinally therethrough to re-
ceive the rule and an opening in its upper 45
side communicating with said bore, of a
spring metal plate at one end of the block
having a yielding portion projecting above
the block, said plate being provided with an
opening corresponding with the bore, ears 50
projecting rearwardly from the yielding up-
per portion of the spring metal plate and
adapted to normally rest upon the block,
and a cam-lever pivoted between the ears,
the cam of the lever being adapted to enter 55
the bore and impinge upon the rule, substan-
tially as shown and described.

2. The combination with a rule, of a gage
device comprising a rectangular block hav-
ing a bore extending longitudinally there-
through to receive the rule and an opening 60
in the upper side communicating with said
bore, said opening being at the front end of
the block, a spring metal plate at the front
end of the block having a yielding portion 65
projecting above the block, said plate hav-
ing openings registering with the bore and
with the opening in the block, ears formed
on and projecting rearwardly from the up-
wardly-projecting portion of the plate at op- 70
posite sides of the opening in the block, and
a cam-lever pivoted between the ears and
arranged so that the cam thereof will im-
pinge against the rule when the handle of the
lever is brought against the upper surface of 75
the block, substantially as shown and de-
scribed.

In testimony whereof I have signed my
name to this specification in the presence of
two subscribing witnesses.

BENJAMIN A. VAUGHN.
